UNITED STATES PATENT OFFICE.

WILLIAM C. MARTEN, OF CARBONDALE, ILLINOIS.

DESIGN FOR A BADGE.

No. 37,963.

Specification for Design.

Patented April 24, 1906.

Application filed December 28, 1905. Serial No. 293,684. Term of patent 14 years.

To all whom it may concern:

Be it known that I, WILLIAM C. MARTEN, a citizen of the United States, and a resident of Carbondale, in the county of Jackson and State of Illinois, have invented a new, original, and ornamental Design for a Badge, reference being had to the accompanying drawing.

The figure of the drawing is a plan view of the badge, showing my new design.

I claim—

The ornamental design for a badge, as shown.

WILLIAM C. MARTEN.
